UNITED STATES PATENT OFFICE.

ABNER K. WOLFE, OF KANSAS CITY, KANSAS, ASSIGNOR OF ONE-HALF TO
GEORGE H. LINDLEY, OF DENVER, COLORADO.

WRENCH.

SPECIFICATION forming part of Letters Patent No. 669,570, dated March 12, 1901.

Application filed May 11, 1900. Serial No. 16,293. (No model.)

To all whom it may concern:

Be it known that I, ABNER K. WOLFE, a citizen of the United States of America, residing in Kansas City, in the county of Wyandotte and State of Kansas, have invented a new and useful Improvement in Wrenches, of which the following is a specification, reference being had therein to the accompanying drawings.

10 My invention relates to improvements in wrenches. It is particularly related to the style of wrenches termed "monkey-wrenches."

The object of my invention is to provide a wrench in which the sliding jaw may be 15 quickly and easily adjusted upon the shank to any position desired.

The invention comprises the combination, with the ordinary shank having a fixed jaw and a sliding jaw mounted on the shank, of a 20 cam carried by the sliding jaw and operated automatically by the pressure exerted in use upon the sliding jaw, a shank-engaging member on which the cam is adapted to bear, means for normally holding the said member 25 in engagement with the shank, and means for releasing the said member from such engagement.

My invention provides, further, certain 30 novel features of construction, hereinafter fully described and explained.

In the accompanying drawings, which illustrate my invention, Figure 1 represents a longitudinal view partly in section. Fig. 2 represents a side elevation view.

35 Similar letters of reference indicate similar parts.

A represents the shank, provided with the ordinary fixed jaw B. Longitudinally movable upon the shank A is the ordinary sliding jaw C. The right side of the shank, as shown in Fig. 1, is provided with a series of transverse serrations or teeth. It is also provided on the same side with a longitudinal groove D, extending from near the handle of 45 the wrench nearly to the fixed jaw B. In the interior of that portion of the sliding jaw which is disposed on the serrated side of the shank is provided a recess or chamber E, in which is mounted a cam F, the outer end of 50 which is pivotally connected to the sliding jaw C. The pivotal connection which I pre-

fer as the one affording the most simplicity and strength is that in which the outer end of the cam F is in the form of the arc of a circle which fits into a correspondingly-shaped 55 seat provided in the interior wall of the jaw C. To the inner end of the cam F is pivotally mounted in any desirable manner the shank-engaging member G, the side adjacent to the shank being provided with transverse 60 serrations adapted to engage the serrations on the shank. The preferable form of connection between the cam F and the member G is to provide in the member G an arcuate recess in which is pivotally fitted the corre- 65 spondingly-shaped inner end of the cam F. The disposition of the cam F approaches a horizontal position, so that pressure upon the jaw C will tend to force the cam F at right angles to the wrench-shank. This disposi- 70 tion of the cam causes the working pressure on the jaw C to be thrown perpendicular to the axis of the shank instead of causing the strain to be exerted upon the serrations of the member G and the shank in a direction parallel with the axis of the shank. Danger of 75 stripping the said serrations is thus obviated. Any convenient means may be employed for holding the member G normally in engagement with the shank. The means which I prefer to employ is to provide a coil-spring H, the upper end of which rests within an upwardly and inwardly inclined recess provided in the member G. The lower end of the coil-spring H abuts against the inner wall of the jaw C. 80 In order to disengage the member G from engagement with the shank A, I have provided a lever I, the upper end of which extends between the wall of the jaw C and the member G. In order to prevent the member G from 85 being forced inwardly at its upper end without at the same time freeing the lower end of the member G, the lever I is so shaped as to bear upon that portion of the member G horizontally opposite the inner end of the cam F. The lever I is mounted and lengthwise movable in the slot or groove D. It is provided at the point K with a fulcrum projection, which rests upon the bottom of the groove. The lower end of the lever I ex- 90 tends outwardly through a slot L, provided in the lower end of the jaw C, and has pro-

vided on its exterior end a thumb-piece M, by means of which the lever is inwardly depressed.

My invention is operated as follows: By depressing the lower end of the lever I it is rocked on the fulcrum K, the upper end of the lever being forced outwardly and against the member G, which is also outwardly forced and moves also in a downward direction, due 5 to its pivotal connection with the cam F, against the pressure of the spring H. The wedge-like form, as indicated by J in Fig. 1, materially assists the downward and outward movement of the member G by coming in 10 contact with the wall of the recess E. The member G now being free from engagement with the shank, the jaw C may be moved lengthwise to any desirable position upon the shank, at which time the pressure on the 15 20 thumb-piece M is removed, permitting the spring H to again force the member G into engagement with the shank. Pressure now being applied upon the shank-handle for the purpose of tightening a knot or accomplishing other work will have a tendency to force the jaw C downward on the shank. The member G, being engaged with the shank, cannot partake of this downward movement, but will remain stationary. The outer end 25 30 of the cam F, however, being free to move with the jaw, will in a degree partake of such movement, and will thus bring into play the cam-locking features of the device. The cam F, being disposed in a nearly horizontal 35 position, will cause the pressure exerted upon the jaw C to be exerted almost perpendicularly to the shank-axis. The greater the pressure thus exerted on the jaw the tighter the member G will be forced against the 40 shank and the more nearly horizontal will become the pressure on the cam F. The configurations of the teeth or serrations in the shank and member G may be such as is desired. In order to more readily release the 45 member from the shank, it is desirable that the teeth be V-shaped, although this is not essential.

My invention is adapted to many modifications while still retaining the spirit thereof.

50 Having thus described my invention, what I claim, and desire to secure by Letters Patent, is—

1. A wrench comprising a shank provided with a fixed jaw, transverse serrations on one side of the shank, and a longitudinal groove 55 in the shank, a slidable jaw mounted upon the shank, a shank-engaging member carried by the slidable jaw, a swinging member pivotally connected with the shank-engaging member and the slidable jaw, and a lever fulcrumed 60 on the shank within the said longitudinal groove, and bearing upon the shank-engaging member at one end and having its free end depressible, substantially as described.

2. A wrench comprising a shank provided 65 with a fixed jaw and having a longitudinal groove in one side, a slidable jaw mounted upon the shank, means for locking the slidable jaw in engagement with the shank, and a lever fulcrumed in the shank-groove and movable 70 with the slidable jaw and coöperating with the shank-engaging means for releasing the slidable jaw from engagement with the shank, substantially as described.

3. A wrench comprising a shank provided 75 with a fixed jaw and having a longitudinal groove in one side, a slidable jaw mounted upon the shank, a shank-engaging member carried by the slidable jaw, means for forcing the said member into engagement with the 80 shank and a lever fulcrumed in the shank-groove and movable with the slidable jaw and bearing upon the said shank-engaging member, substantially as described.

4. A wrench comprising a shank provided 85 with a fixed jaw and having a longitudinal groove in one side, a slidable jaw mounted upon the shank, the shank-engaging member G carried by the slidable jaw, the cam F, pivotally connected to the member G and the 90 slidable jaw, a spring for forcing the member G into engagement with the shank and a lever I fulcrumed in the groove of the shank, bearing upon the member G and movable with the slidable jaw, substantially as de- 95 scribed.

In testimony whereof I have signed my name to this specification in the presence of two subscribing witnesses.

ABNER K. WOLFE.
